(57) **CLAIM**

The ornamental design for a micro traxion progress capture pulley, as shown and described.

DESCRIPTION

FIG. 1 is a front, top, right-side perspective view of a micro traxion progress capture pulley;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof;

FIG. 8 is a front, top, right-side perspective view thereof with an engagement portion extended in an alternate configuration of use; and,

FIG. 9 is a front, top, right-side perspective view thereof with a front side portion rotated and the engagement portion extended into another alternate configuration of use.

The broken lines depict environmental subject matter only and form no part of the claimed design.
